LOOM PICKER MANUFACTURE

Henry Miles Bacon, Warren, Ohio

Application May 14, 1937, Serial No. 142,598

10 Claims. (Cl. 139—159)

This invention relates to improvements in loom pickers of laminated construction and more particularly to pickers built up of sheets of rubberized fabric stuck together in layers while in the uncured state, and then molded and vulcanized to produce a tough, elastic, solid and homogeneous picker body. An example of this type of picker is disclosed in my U. S. Patent No. 2,032,734, dated March 3, 1936.

10 Important objects of the invention are to provide such a picker of improved, durable construction, and to provide an improved method of making such a picker.

Other objects of the invention will appear hereinafter.

In the drawing:

Figs. 1, 2 and 3 are sectional perspective views showing different stages of picker manufacture according to the improved method;

20 Figs. 4 and 5 are enlarged sectional perspective views showing more advanced stages of the manufacture;

Fig. 6 is a sectional view showing a modification of one stage of the manufacture;

25 Fig. 7 is a side view of a bar of laminated construction from which a number of pickers are made, the severance of the bar into individual pickers being indicated;

Fig. 8 is a sectional view showing the molding 30 of a pair of the pickers;

Fig. 9 is a longitudinal sectional view of a finished picker, on the line 9—9 of Fig. 10; and

Fig. 10 is a bottom plan view of the finished picker.

35 In the performance of the improved method a plurality of sheets 1 are provided. These sheets are impregnated with a rubber composition in a sticky, uncured state. Preferably the sheets are of a length equal to the depth of quite a number 40 of pickers in order that a number of pickers may be made simultaneously. The width of the sheets is sufficient for a wrapping operation which will be described hereinafter.

The rubberized sheets 1 are superimposed and 45 their medial portions are bent or folded around a core 2 into a loop of approximately U-form, as shown in Fig. 1. The cross section of said core has approximately the size and shape of a hole which is to be formed in the picker to receive the picker stick, indicated by dot-and-dash lines at S in Fig. 9. The sheets so folded extend materially beyond the U-shaped loop and their margins 3 are preferably left free, or unstuck, for a purpose which will appear hereinafter. As 50 indicated at 4, one or more of the sheets may be

doubled upon themselves at the bend of the U-loop for purposes which will appear hereinafter.

Upon sheet 1 there are placed a number of superimposed fabric sheets 5 rubberized like the sheets 1. The sheets 5 are of the same length as the sheets 1 but narrower than the latter and they are placed across the open side of the U-shaped loop of the sheets 1, the margins 3 of the sheets 1 being left free, as indicated in 5 Fig. 2. Next, the sheets 1 and 5 are securely united by stitching 6 which extends the length of the sheets on parallel lines along opposite sides of the top of the U-shaped loop. Preferably very strong thread or even wire is employed in the stitching. After the stitching has been performed there are placed upon the sheets 5 superimposed narrow fabric strips 7 rubberized like the sheets 1 and 5. They are placed in centered relation to the U-loop and the lines of stitching 6 and 10 they extend the length of the sheets 1 and 5. These strips are for the purpose of forming a filler block for each picker and located between the picker stick hole and the shuttle impact face of 15 the picker.

Having so associated the sheets 1 and 5 and the 20 filler strips 7, the sheets 5 are next folded entirely around the strips in the same direction as the folding of the sheets 1 in forming the U-loop, and the opposite margins of the sheets 5 are 25 completely overlapped as shown in Fig. 4. Thus the sheets 5 form a complete transverse wrapping for the strips 7. Next, the side portions of the sheets 1 which extend beyond the U-loop are 30 folded forward around three sides of the wrapped 35 filler strips, and the margins 3 are overlapped alternately, or interleaved as shown. Around the entire structure thus formed by the sheets 1 and 5 and the strips 7 there is folded an outer wrapping 40 comprising a number of superimposed fabric sheets 8 rubberized like the sheets 1 and 5. These outer sheets are of the same length as the sheets 1 but wide enough to enable their margins 9 to 45 overlap and form the forward shuttle impact wall structure of the picker. The margins 9 are preferably at first left free or unstuck so that, like the margins 3, they may be interleaved, as shown in Fig. 5. The outer wrapping covers and protects the lines of stitching 6. One or more of the sheets 50 8 also may be doubled upon themselves, as at 10. A modification of the outer wrapping is shown 55 in Fig. 6. Here the wrapping is formed of a single wide sheet 8a of fabric rubberized like the other sheets. Said wide sheet is wound a number of

times around the structure formed by the sheets 1 and 5 and the strips 7.

Whether the structure is like that of Fig. 5 or of Fig. 6 the assembled sheets and strips are stuck together by the sticky, uncured rubber and the structure forms a tubular bar, as shown in Fig. 7. The core 2 is removed from this bar and the bar is then severed on transverse lines 11 spaced apart according to the desired approximate depth of a picker. Thereby a number of picker bodies are obtained. These are molded and vulcanized to the desired picker form and to the desired degree of hardness.

The picker bodies may be conveniently molded in pairs, as shown in Fig. 8. Provision is also made for molding the front portion of the picker in a manner to give increased durability. For this purpose there is provided a tapered mold core 13 for insertion into the stick hole of the picker body. As shown in Fig. 8, there are two of these cores borne by a bar or block 14 and protruding from opposite sides thereof. The cores and block may be made of a single piece of metal. The cores taper away from the block so that they may readily enter the stick holes of the picker bodies. After applying the picker bodies to the cores the assembled unit of cores, block and picker bodies is fitted into a mold casing 15, for molding and vulcanizing the bodies under pressure and heat. The cores, the block 14 and the mold casing are correlated for molding the forward face of the picker and the forward wall of the stick hole along divergent lines. The core taper is so disposed as to mold the forward portion of the picker under pressure which varies along the depth of the picker. This pressure gradually increases from the upper side of the picker to the lower side, and the fore-and-aft width of the forward portion gradually diminishes from top to bottom, as shown in Fig. 9.

Thereby the laminations are forced closer together at the lower front portion of the picker and this gives greater density and hardness to the lower portion and adds to the durability of the picker, as will be explained hereinafter. By varying the degree of taper of the mold core said increased hardness may be varied to suit requirements. As shown in Fig. 9, the forward face of the picker P has a substantially conical cavity 16 to receive the nose of the shuttle. This cavity may be molded in said face by projections 17 on one of the sections of the mold casing. After the picker body has been molded it may be cut away to provide a desired slope 18 to its under side.

A loom picker constructed as shown and described has great durability. One feature of durability is the provision for secure retention of the filler structure. The filler block formed by the strips 7 and the wrapping sheets 5 for said block are securely held in a continuous loop formed by the wrapping sheets 1 and 8. These sheets 1 and 8 form a strong, multi-ply wrapping covering the filler structure at front and sides and also combining with the inner side of said structure to define the picker stick hole. In many cases, owing to imperfect alignment in the loom, a picker will rub against a shuttle box and wear away a forward corner and a side of the picker body until the outer wrappings are worn through and the filler structure is released. My improved picker structure is designed to withstand much more of such wear and retain the filler in place. The entire thickness of the stout side walls of the picker stick hole extends around the filler and protects it, and the front wall

structure is further reinforced by the overlapped margins of the wrapping sheets 1 and 8.

The tapered molding of the forward portion of the picker also contributes much to durability. In the majority of cases present pickers require the shuttle to strike below the center of the picker face. Consequently there is less material below the point of impact than above it and the picker wears out more rapidly below said point. My provision for greater density of the lower portion of the face block greatly increases the wear resistance of said portion and thereby lengthens the life of the picker. The portion of the block at the under side of hole 16 has much more wear resistance than the portion above the hole. Consequently the wear tends to travel and the hole, as it is borne deeper and deeper, tends to rise rather than assume a straight line toward the back of the block.

The back-laps 4 and 10 add strength to the portion of the picker back of the picker stick hole. In operation a picker, on its back stroke, often hits a lay strap. The wear of this impact sometimes cuts the picker through. The additional plies provided by the fold-backs 4 and 10 enables the back of the picker to be molded to greater density in order to better resist said wear. The fold-backs also facilitate proper molding of the picker. They hold up the mold core unit and prevent it from bottoming on the lower section of the mold casing with possible consequent forcing of the cores out of proper relation to the picker bodies. The cores are held balanced, with regard to pressure, between the top and bottom cushions and the molding pressure is substantially equalized along the lines of stitching 6.

What I claim is:

1. The method of making a loom picker, comprising superposing a number of sheets of rubberized fabric, bending a medial portion of said superposed sheets to form an approximately U-shaped loop as a step in forming the picker stick hole, placing a plurality of rubberized fabric sheets in superposed relation upon said first sheets and in a position across the open side of said loop, placing upon the portion of said superposed second sheets which extends across the open side of the loop superposed layers of rubberized fabric to form a filler block, folding said second sheets around said superposed filler block layers, folding the portions of said first sheets which extend from said loop forward around the so folded second sheets and disposing the end margins of said portions to form the forward, shuttle impact portion of the picker, and reducing the structure so formed to picker form by a molding and vulcanizing operation.

2. The method of making a loom picker according to claim 1, characterized in that the molding operation is performed to compress the lower front portion of the picker to a greater hardness than the upper front portion, for increasing the durability of the picker.

3. The method of making a loom picker, comprising superposing a number of sheets of rubberized fabric, bending a medial portion of said superposed sheets to form an approximately U-shaped loop as a step in forming the picker stick hole, placing a plurality of rubberized fabric sheets in superposed relation upon said first sheets and in a position across the open side of said loop, stitching said second sheets to said first sheets along opposite sides of the loop opening,

5 placing upon the portion of said second sheets which extends across the open side of the loop superposed layers of rubberized fabric to form a 5
filler block, folding said second sheets around said superposed filler block layers, folding the portions of said first sheets which extend from said loop around the so folded second sheets and interleaving the outer ends of said portions at the front of the picker, and molding and vul- 10
canizing the structure so formed.

10 4. The method of making a loom picker, comprising providing a number of superposed sheets of rubberized fabric, bending a medial portion of said superposed sheets to form an approximately 15
U-shaped loop as a step in forming the picker stick hole, placing a sheet of rubberized fabric upon said first sheets and in a position across the open side of said loop, placing upon the portion of said second sheet which extends across the 20
open side of the loop material to form a filler block, folding said second sheet around said filler block material, folding the portions of said first sheets which extend from said loop around the so folded second sheet and overlapping the 25
outer ends of said portions at the front of the picker, and molding and vulcanizing the structure so formed.

25 5. The method of making a loom picker, comprising providing a number of superposed layers 30
of fabric, with a bonding material to unite them, bending a medial portion of said superposed layers to form an approximately U-shaped loop as a step in forming the picker stick hole, placing a plurality of fabric layers in superposed relation, 35
and with a bonding material to unite them, upon said first layers and in a position across the open side of said loop, stitching together said first and second layers along opposite sides of the loop opening, placing material for forming a filler 40
block upon the portion of said superposed second layers which extends across the open side of the loop, folding said second layers around said filler block material, folding the portions of said first layers which extend beyond said loop around the 45
so folded second layers, and molding the structure so formed to a picker shape.

45 6. The method of making a loom picker, comprising superposing a number of layers of fabric, with a bonding material to unite them, bending a 50
medial portion of said superposed layers to form an approximately U-shaped loop as a step in forming the picker stick hole, placing a plurality of fabric layers in superposed relation, and with a bonding material to unite them, upon said first 55
layers and in a position across the open side of said loop, stitching together said first and second layers along opposite sides of the loop opening, placing material for forming a filler block upon the portion of said superposed second layers 60
which extends across the open side of the loop, folding said second layers around said filler block material, folding the portions of said first layers which extend beyond said loop around the so folded second layers, surrounding said so folded 65
first layers with a fabric wrapping thereby covering said stitching, and molding the structure so formed to a picker shape.

7. The method of making a loom picker, comprising superposing a number of layers of fabric, with a bonding material to unite them, bending a medial portion of said superposed layers to form an approximately U-shaped loop as a step 5
in forming the picker stick hole, placing a plurality of fabric layers in superposed relation, and with a bonding material to unite them, upon said first layers and in a position across the open side of said loop, placing material for forming a 10
filler block upon the portion of said superposed second layers which extends across the open side of the loop, folding said second layers around said filler block material, folding the portions of said first layers which extend beyond said loop 15
around the so folded second layers, and molding the structure so formed to picker shape.

8. The method of making a loom picker, comprising providing a number of superposed layers of fabric, with a bonding material to unite them, 20
bending a medial portion of said superposed layers to form an approximately U-shaped loop as a step in forming the picker stick hole, placing a plurality of fabric layers in superposed relation, and with a bonding material to unite 25
them, upon said first layers and in a position across the open side of said loop, placing material for forming a filler block upon the portion of said superposed second layers which extends across the open side of the loop; folding said second 30
layers around said filler block material, and folding the portions of said first layers which extend beyond said loop around the so folded second layers.

9. The method of making a loom picker, comprising arranging plies of rubberized fabric in superposed relation to form a non-tapered picker-stick receiving loop and the front portion of the picker which receives the impact of the shuttle, inserting a tapered core in said non-tapered loop of the picker and molding said 35
picker to shape the picker-stick hole and form the forward face of the picker, the forward wall portion of the picker being molded along divergent lines so as to compress the shuttle impact 40
face of the picker to greater hardness and less thickness from the front to rear below the point of shuttle impact than above that point, and vulcanizing said compressed molded product to 45
produce a picker wherein the lower front portion is of greater density and hardness than the upper front portion.

10. The method of making a loom picker, comprising arranging plies of rubberized fabric in superposed relation to form a non-tapered 55
picker-stick receiving loop and a front part which engages the shuttle, inserting a tapered core in said non-tapered loop of the picker, placing a conical projection in said front part of the picker to form a cavity to receive the shuttle nose, and molding said picker to shape the picker, said front part of the picker being held between converging mold surfaces to compress said part to a greater density and hardness below said cavity than above the cavity, and vulcanizing said com- 60
pressed molded product.

HENRY MILES BACON.
